CLAIM

The ornamental design for a beverage cooler, as shown and described.

DESCRIPTION

FIG. 1 is a top, left side, front perspective view of a beverage cooler;

FIG. 2 is a bottom, left side, rear perspective view of the beverage cooler;

FIG. 3 is a front view of the beverage cooler;

FIG. 4 is a rear view of the beverage cooler;

FIG. 5 is a left side view of the beverage cooler;

FIG. 6 is a right side view of the beverage cooler;

FIG. 7 is a top view of the beverage cooler; and,

FIG. 8 is a bottom view of the beverage cooler.

The broken lines shown in drawings represent unclaimed portions of the beverage cooler and form no parts of the claimed design.

1 Claim, 8 Drawing Sheets
